VESSEL AND TRACK CONSTRUCTION FOR
REFRIGERATORS

Alvie C. Crimmel, Hartford City, Ind.

Application July 21, 1932. Serial No. 623,835

12 Claims. (Cl. 221—68.)

This invention relates to a tilttable and slideable liquid container associated with a support included in a refrigerator.

The chief object of this invention is to provide a refrigerator with a suitable track construction for sustaining a liquid container, such as a water bottle, which bottle may be slid along the support toward the back of the refrigerator and toward the door opening or front of the refrigerator when it is desired to remove part of the contents of the bottle, the support and the bottle having a cooperating relationship, whereby the bottle may be prevented from lateral tilting, while supported in the refrigerator but may be readily slid toward the door opening for pouring purposes, and may be readily tilted when adjacent the door opening, all without removing the bottle from the refrigerator, whereby the bottle need not be removed from the refrigerator except when empty and for refilling, or otherwise as desired.

Another object of the invention is to provide a support or trackway such that the outward sliding movement of the bottle is limited, thereby preventing accidental complete outward movement of the bottle and disassociation from the support except when disassociation is desired.

The chief feature of the invention consists in the formation of the support and trackway construction and the cooperating parts of the bottle, whereby the aforesaid objects are accomplished.

Other features of the invention will appear more fully hereinafter as set forth.

The full nature of the invention will be understood from the accompanying drawing and the following description and claims:

In the drawing, Fig. 1 is a central sectional view through a portion of a refrigerator equipped with the invention, the full lines showing the bottle, the stopper being removed, and in its normal position within the refrigerator, and the dotted lines indicating a pouring position of the bottle when it is not removed from the refrigerator. Fig. 2 is a transverse sectional view through the support with the bottle shown in front elevation and in normal stationary position. Fig. 3 is a view similar to Fig. 1, of a modified form of the invention. Fig. 4 is an end elevation of the bottle and support in tilted position, and of the modification shown in Fig. 3.

In Figs. 1 and 2 of the drawing, 10 indicates a refrigerator, 11 the opening into the same, and 12 a chamber in the refrigerator. Suitably sup-

ported by the refrigerator is a pair of spaced straight tracks in the form of rods 13. Slidably supported on the rods 13 is a water bottle having a substantially cylindrical body portion 14, an upstanding neck 15 with a mouth 16 of appreciable area, and if desired provided with a lip 16a. The mouth may be positioned vertically on the bottle or may be inclined, as illustrated. Each side wall of the bottle includes a pair of outwardly projecting relatively large area portions 17 and a smaller outer peripheral portion 18 connected by a substantially cylindrical wall portion 19. The cylindrical body wall 14 is shown flattened as at 20. The flattened base portion 20 serves to support the bottle when it is not supported upon the trackways. The flattened portion 21 serves to support the bottle in non-tiltable relation on the trackways. The body portion 14 thus is nested between the trackways at its lowest portion when the bottle is mounted on the trackways, and the bottle may be slid from the full line position shown in Fig. 1 to the dotted line position shown in the same figure and thereafter tilted at the end of said movement, or may simultaneously be tilted in the withdrawal movement.

In the modification shown in Figs. 3 and 4, substantially the same type of bottle is utilized. In said figures all of the similar parts are indicated by numerals of the 100 series. In this form of the invention, however, each trackway includes a depressed or downwardly-extending curved portion 131 and this is positioned near the opening of the refrigerator so that the bottle when slid outwardly along the trackway toward the opening of the refrigerator, will nest in the arcuate portion 131 and then may be readily tilted therein for pouring. Likewise this type of trackway prevents accidental escapement of the bottle during the pouring operation.

The bottle need not be provided with the flattened bottom portion 20 or 120, but then the bottle will not be self-sustaining when positioned upon a flat surface support. Preferably, however, the flat bottom is provided. Likewise, in most instances, the flattened portion 20 or 120 should be provided upon the large side areas or side walls.

The invention claimed is:

1. In combination with a pair of spaced substantially horizontal trackways, a receptacle slidably and tiltably supported thereon and partially depending between the same, including a peripheral body wall positioned between the trackways and terminating in a relatively large

- upwardly directed mouth, opposite substantially flat sides, and connections between the sides and body, said connections being arranged for supporting the receptacle upon the trackway and being a concave fillet with a comparatively sharp inner squared corner. 5 a peripheral body wall positioned between the trackways and terminating in a relatively large upwardly directed mouth, opposite substantially flat sides, and connections between the sides and body, said connections comprising concave fillets arranged for supporting the receptacle upon the trackway, the connections each including a flattened bottom portion. 80
2. In combination with a pair of spaced substantially horizontal trackways, each having a curved depressed portion near one end thereof, a receptacle slidably and tiltably supported thereon, and partially depending between the same including a peripheral body wall terminating in a relatively large mouth, opposite substantially flat sides, and connections between the sides and body and arranged for supporting the receptacle upon the trackways and cooperating with the depressed portions of said trackway for tilting of the receptacle without sliding thereof, each connection being a concave fillet with a comparatively sharp inner squared corner. 10 85
3. A receptacle including a peripheral body wall having a substantially flat bottom for self sustaining purposes and a relatively large upwardly directed mouth, opposite substantially flat sides, and a connection between each side and the body wall including a concave fillet having a comparatively sharp inner squared corner. 15 90
4. In combination with a pair of spaced substantially horizontal trackways, a receptacle slidably and tiltably supported thereon and partially depending between the same, including a peripheral body wall positioned between the trackways and terminating in a relatively large upwardly directed mouth, opposite substantially flat sides, and connections between the sides and body, said connections being arranged for supporting the receptacle upon the trackway, the peripheral body wall having a flattened base portion and each connection comprising a concave fillet having a comparatively sharp inner squared corner. 20 95
5. In combination with a pair of spaced substantially horizontal trackways, each having a curved depressed portion near one end thereof, a receptacle slidably and tiltably supported thereon and partially depending therebetween, including a peripheral body wall terminating in a relatively large mouth, opposite substantially flat sides, and connections between the sides and body and arranged for supporting the receptacle upon the trackways and cooperating with the depressed portions of said trackway for tilting of the receptacle without sliding thereof, the peripheral body wall having a flattened base portion and the connections each including a flattened bottom portion. 25 100
6. A receptacle including a peripheral body wall having a substantially flat bottom for self sustaining purposes and a relatively large upwardly directed mouth, opposite substantially flat sides, and a connection connecting each side to the body wall, the peripheral body wall having a flattened base portion, and each connection comprising a concave fillet having a comparatively sharp inner squared corner. 30 105
7. In combination with a pair of spaced substantially horizontal trackways, a receptacle slidably and tiltably supported thereon and partially depending between the same, including a peripheral body wall positioned between the trackways and terminating in a relatively large upwardly directed mouth, opposite substantially flat sides, and connections between the sides and body, said connections comprising concave fillets arranged for supporting the receptacle upon the trackways and cooperating with the depressed portions of said trackway for tilting of the receptacle without sliding thereof, the peripheral body wall having a flattened base portion and the connections each including a flattened bottom portion. 35 110
8. In combination with a pair of spaced substantially horizontal trackways, each having a curved depressed portion near one end thereof, a receptacle slidably and tiltably supported thereon and partially depending therebetween, including a peripheral body wall terminating in a relatively large mouth, opposite substantially flat sides, and connections between the sides and body and comprising concave fillets arranged for supporting the receptacle upon the trackways and cooperating with the depressed portions of said trackway for tilting of the receptacle without sliding thereof, the connections each including a flattened bottom portion. 40 115
9. A receptacle including a peripheral body wall having a substantially flat bottom for self sustaining purposes and a relatively large upwardly directed mouth, opposite substantially flat sides, and a connection connecting each side to the body wall and comprising a concave fillet, the connections each including a flattened bottom portion. 45 120
10. In combination with a pair of spaced substantially horizontal trackways, a receptacle slidably and tiltably supported thereon and partially depending between the same, including a peripheral body wall positioned between the trackways and terminating in a relatively large upwardly directed mouth, opposite substantially flat sides, and connections between the sides and body, said connections comprising concave fillets arranged for supporting the receptacle upon the trackway, the peripheral body wall having a flattened base portion and the connections each including a flattened bottom portion. 50 125
11. In combination with a pair of spaced substantially horizontal trackways, each having a curved depressed portion near one end thereof, a receptacle slidably and tiltably supported thereon and partially depending therebetween, including a peripheral body wall terminating in a relatively large mouth, opposite substantially flat sides, and connections between the sides and body and comprising concave fillets arranged for supporting the receptacle upon the trackways and cooperating with the depressed portions of said trackway for tilting of the receptacle without sliding thereof, the peripheral body wall having a flattened base portion and the connections each including a flattened bottom portion. 55 130
12. A receptacle including a peripheral body wall having a substantially flat bottom for self sustaining purposes and relatively large upwardly directed mouth, opposite substantially flat sides, and a connection connecting each side to the body wall, the peripheral body wall having a flattened base portion and the connections each including a flattened bottom portion. 60 135
